(57) CLAIM

The ornamental design for a handbag, as shown and described.

DESCRIPTION

The patent or application file contains at least one photograph executed in color. Copies of this patent or patent application publication with color photograph(s) will be provided by the Office upon request and payment of the necessary fee.

FIG. 1 is a front left perspective view of a handbag showing my new design;

FIG. 2 is a front elevation view thereof;

FIG. 3 is a rear elevation view thereof;

FIG. 4 is a left side view thereof;

FIG. 5 is a right side view thereof;

FIG. 6 is a top plan view in an alternate configuration, where the top handles are rotated downward and rest on the front and rear sides; and,

FIG. 7 is a bottom view of the configuration shown in FIG. 5.
